UNITED STATES PATENT OFFICE.

CHARLES MILLS, OF NEWTON UPPER FALLS, MASSACHUSETTS, ASSIGNOR TO WILLIS C. SWIFT, OF FITZWILLIAM, NEW HAMPSHIRE.

MOLDING-MACHINE.

1,000,103.

Specification of Letters Patent. Patented Aug. 8, 1911.

Application filed May 6, 1903. Serial No. 155,869.

To all whom it may concern:

Be it known that I, CHARLES MILLS, a citizen of the United States, residing at Newton Upper Falls, in the county of Middlesex and 5 State of Massachusetts, have invented a certain new and useful Improvement in Molding-Machines, of which the following is a specification.

My invention relates to molding machines 10 and has for its object to provide a new and improved machine of this description.

My invention is illustrated in the accompanying drawings, wherein—

Figure 1 is an end view of a machine embodying my invention showing the pattern in outline and the flask broken away; Fig. 2 is a side view of the same the pattern and flask being omitted; Fig. 3 is a section on line 3—3, Fig. 2; Fig. 4 is a section on line 20 4—4, Fig. 2; Fig. 5 is a section on line 5—5, Fig. 2; Fig. 6 is a vertical sectional view through the stripping plate, flask and pattern.

Like letters refer to like parts throughout 25 the several figures.

Referring now to the drawings, wherein I have shown one form of my invention, I provide two side pieces A and B, each of a single piece and extending from the stripping plate C to the floor. Between the side pieces and rigidly attached thereto is a stationary piece or frame D, upon which is mounted the shaft D¹. This part D may be connected to the side pieces A and B in any 30 desired way, as by means of the bolts D². The side pieces A and B are connected at the bottom by means of the rods or bolts A¹. These rods are supplied with screw-threads and adjusting nuts, so that the position 35 of the side pieces may be adjusted. These side pieces and the piece D and the rods A¹ form what may be termed the main frame of the machine. The side pieces A and B are provided on their inner faces with 40 guides A² and B² (see Fig. 2), which project therefrom and form guide-ways on the side pieces. Within the main frame is a movable or sliding frame, consisting of the bottom frame G, the pattern plate E, the 45 pattern plate supporting pieces E¹ and the rods F attached to the pattern plate supporting pieces at one end and adjustably attached to the bottom frame G at the other end. The pattern plate supporting pieces 50 55 support the pattern plate and are provided

with guides E², which engage the guide-ways in the side pieces of the main frame (see Fig. 5). This bottom frame G is provided with holes at the corners, through which the rods F pass, and is provided with guides G¹, which coöperate with the guide-ways on the side pieces A and B formed by the projections A² and B². The shaft D¹ is provided with two cranks G⁴, one near each side of the main frame, and a pin G⁶ 60 extends through these two cranks connecting them together. A shaft G² is mounted in the bottom frame G and a connecting piece G³ has one end connected to said shaft and the other to the cranks G⁴, said connecting piece filling the space between the two cranks. This construction gives a gearing which occupies substantially the whole of the space between the sides of the frame, and thus provides extended bearing surfaces 65 to take up the thrust or shock produced by ramming the sand in the flask. The rods F are each adjustably connected to the bottom frame G in any desired manner, so that said frame may be moved up and down there- 70 along to secure the correct adjustment of the height of the movable frame in the construction and assembling of the machine and for taking up the wear which may occur in the use of the machine. By means of these rods, 75 each of the corners of the inner frame are separately adjustable, rendering it possible to easily build a machine which will be absolutely accurate. One machine may be adapted for draws of various lengths by 80 simply changing the height of the main frame piece D and the length of the cranks G⁴ in a corresponding manner.

The stool plate D³ is connected to the stationary frame piece D and is formed so as 85 not to interfere with the movement of the movable inner frame, the sliding pattern plate rails passing by the stool plate in descending. This stool plate acts to support any stools that may be necessary when a 90 pattern requiring stools is used.

The guides A² and B² and the inner faces of the side pieces A and B are finished throughout their entire length, so that the main frame piece D may be raised or lowered in adjusting the machine to adapt it to the conditions presented, or the movable frame drawn, and yet be provided with proper guide-ways and locating parts.

In Fig. 1 I have shown a simple form of 110

pattern E⁴ in position on the pattern plate E, and a stool E⁵ supported on the stool plate D⁶. It is of course evident that any desired form of pattern can be used, and I have shown a simple form for purposes of illustration. In Fig. 6 I have shown the parts in position, including the flask E⁶.

In assembling the machine, the side pieces A and B are set up and fastened together by the rods A¹ and the main frame piece D. The inner frame is then assembled and placed in position and connected with the main frame by the connecting piece and the parts adjusted in the desired manner.

It will be noted that the upper and lower ends of the movable inner frame are provided at each corner with guides, which engage the guides on the main frame and that the adjustable rods F passing through holes in the stationary part D form additional intermediate guides between said upper and lower guides. The guides A² and B² at each corner are preferably made integral with said frame and extend substantially along the entire length thereof and in addition to serving as guide-ways top and bottom for the movable inner frame act also as surfaces for accurately locating the parts of the stationary frame.

In the operation of the device the parts are moved so that the pattern plate is in the position illustrated in Fig. 2, that is, up close to the stripping plate. The flask is then placed in position and the sand rammed about the pattern. The pattern is then withdrawn from the flask by the operator moving the handle, so as to rotate the shaft D¹. This shaft, through the agency of the cranks G⁴, the connecting piece G³, and the shaft G², moves the pattern plate and pattern downwardly, as the shaft G² is connected with the bottom frame piece G fastened to the pattern plate frame. The pattern is then withdrawn from the flask.

By means of this construction, I am enabled to provide a simple, rigid machine, having large and extended bearing surfaces for all movable parts, which may be quickly and easily and accurately adjusted, and a machine that may be easily manufactured and easily assembled. It will further be noted that this machine will take a long stool plate.

I have described in detail a particular construction embodying my invention, but it is of course evident that the parts may be varied to suit varying conditions and such variations will readily suggest themselves to those versed in the art.

In the operation of the device the flask is placed in position and the pattern plate moved up to its top position. The sand is then rammed into the flask. The shaft D¹ is then rotated so as to move the pattern,

pattern plate and associated parts to withdraw the pattern from the sand.

I claim:

1. A molding machine comprising a main frame having side pieces provided with guides extending therealong, a movable frame with guides associated therewith, a connecting part between the two side pieces of the main frame, the guides on the side pieces serving also to locate the connecting piece and fix its position in assembling the machine. 70

2. A molding machine, comprising an inner frame, consisting of a pattern plate, movable pattern plate rails to which the plate is connected, a sliding frame piece connected to said pattern plate rails and provided with a shaft, a main frame, comprising two side pieces, a stationary frame piece connected thereto and located between the pattern plate and the sliding frame piece, a shaft mounted on said frame piece and provided with a crank, and a connecting piece between the crank and the shaft on the movable frame. 80

3. A molding machine, comprising a main stationary frame, an inner movable frame carrying the pattern plate and provided at each corner with a rod, and a lower sliding piece adjustably connected with said rods and having a sliding connection with the frame, so that the length of said inner frame may be adjusted, and a connection between the two frames whereby one may be moved with relation to the other. 90

4. A molding machine comprising a main frame and a pattern carrying frame, the pattern carrying frame provided at each corner with adjusting means by which the pattern carrier may be adjusted independent of the connection or the crank by which motion is communicated to it, whereby the corners of the pattern carrier may be separately adjusted. 105

5. A molding machine, comprising a main frame and a movable frame, said main frame provided with extended guide-ways at each corner, the movable frame provided at each corner at the top and bottom with guides which engage said guide-ways, the two sets of guides at the top and bottom separated by an intervening space, said guide-ways forming part of the supporting frame. 115

6. A molding machine, comprising a main frame, provided at each corner with guide-ways which extend substantially from top to bottom, an intermediate stationary part provided with engaging pieces which engage said guide-ways, so as to fix the relative position of the parts of the main frame, and a movable frame provided with guides which engage said guide-ways on each side of the intermediate stationary part. 125

7. A molding machine, comprising an in- 130

- ner frame made up of a pattern plate, pattern plate rails and a frame adjustably connected to the pattern plate rails so as to be capable of vertical adjustment, and an outer frame provided on its inner faces with guide-ways extending below the inner frame, and suitable guides on the inner frame engaging said guide-ways.
8. A molding machine comprising a main frame made up of two side pieces with an intermediate connecting piece, the side pieces provided with inwardly projecting guides, a connecting piece connecting the two side pieces together, the parts arranged so that the guides serve to locate the connecting piece in assembling the machine.
9. A molding machine having a fixed frame comprising two side pieces which act as supports for the machine, a connecting piece between them, a shaft mounted upon the connecting piece, a movable frame associated with said side pieces having one portion above the connecting piece, and an

other portion below the connecting piece, and a shaft on said movable frame, both of said shafts being substantially parallel with the said side pieces.

10. A molding machine, comprising an inner frame made up of a pattern plate, pattern plate rails, a frame piece adjustably connected to the pattern plate rails so as to be capable of vertical adjustment, and an outer frame provided on its inner face with guide-ways extending below the inner frame, and suitable guides on the inner frame engaging said guide-ways, the parts of the outer frame carrying the guide-ways adjustably connected together, so that they can be adjusted to bring the guide-ways into proper relation with the movable frame.
